FIRING MECHANISM BARRIER

Wilfred E. Thibodeau, Cleveland, Ohio, and
Gregory J. Kessenich, Madison, Wis.

Application January 24, 1941, Serial No. 375,800

7 Claims. (Cl. 102—79)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to projectile fuses and in particular to a new type of safety member for the same.

Broadly, the invention consists in providing for the primer in a fuse, a protective member of material which is soft-rubber-like in its physical properties such as resilience and high elastic deformation. Any natural or synthetic rubber may be used, or any other rubber-like product of the general type of polymerized hydrocarbons having elastic properties similar to soft rubber. Such a material will undergo tremendous changes in shape or form under the action of centrifugal force at bullet rotational velocities and such changes can be utilized to place a fuse in armed condition. This form of fuse can return to unarmed condition after rotation has abated, and will not explode on falling to earth. The fuse of the invention is especially useful in firing from aircraft at short ranges, the fuse being armed during the interval represented by such ranges.

It is therefore an object of this invention to provide a fuse having a safety member of a material soft-rubber-like in its physical properties, so utilized in the fuse as to deform under centrifugal force to arm the fuse.

It is another object of the invention to provide a fuse as above which will also be unarmed on abatement of rotation.

To these and other ends, the invention consists in the construction, arrangement and combination of elements described hereinafter and pointed out in the claims forming a part of this specification.

A practical embodiment of the invention is illustrated in the accompanying drawing wherein:

Figure 1 is a sectional view in elevation of the forward portion of a shell, showing the fuse structure;

Figure 2 is a sectional view on the line 2—2 of Figure 1;

Figures 3 to 8 and 10 are views similar to Figure 1 showing modifications;

Figure 9 is a sectional view on the line 9—9 of Figure 8, and

Figures 11 and 12 are perspective views of modifications of the rubber blocking member.

Referring to the drawing by characters of reference, there is shown in Figure 1 a projectile

body 1 having threadedly attached thereto a nose cap 2. Within the body 1 is an axial bore 3, and, at the base thereof, a smaller bore 4 to accommodate a primer 5. Cap 2 has an axial bore 6 slidably receiving a firing pin 7. Pin 7 may be held in the shell by turning over the edges of bore 6 as at 8. Fitted between a shoulder 9 of the pin 7 and the primer and surrounding the point of pin 7 is a thick rubber tube 10. Surrounding the rubber member in contacting relation and snugly fitting the bore 3 is a cage-like insert consisting of washer-like end members 11 with rod-like uprights 12 affixed thereto. The particular shape of this cage is not critical since any device which will engage the rubber at peripheral points of the latter on dilation will answer the purpose. The rods 12 may be rectangular or any other shape in cross-section and may be integral with the end pieces, or rods 12 may be integral with any part of the fuse, thus eliminating the end pieces 11.

On rotation, the rubber commences to distend into the spaces 13 between rods 12, the rods serving to maintain the rubber in rotation. On distension, the central hole 14 in the rubber opens to free the pin 7. If no impact occurs the rubber will eventually return to safe position.

Referring to Figure 3 there is shown a fuse having a shell body portion 15 and a nose cap 16 threadedly attached thereto. Through cap 16 and into body 15 is a bore 17 and slidably fitted in bore 17 is a firing pin 18. A primer 19 is located in a recess at the bottom of bore 17. Complementary recesses in the cap 16 and body 15 define a U-shaped annular channel 20. Inserted in the body at intervals around the recess and extending across the channel are pins 21. Inside the circle of pins 21 and extending into a groove 22 in the pin 18 is a rubber band 23 of circular section. This rubber member may also be rectangular in section, or any other convenient shape. The resistance to shear of the rubber member will hold the firing pin safe under all ordinary conditions, but on rotation the rubber member will distend into the channel and free the pin.

In Figure 4 is shown a projectile 24 having threadedly attached thereto a nose cap 25. The cap has an outer bore 26 in which a firing pin 27 is slidably fitted and an inner tapering bore 28. A primer carrier 29 is threadedly or otherwise attached in the lower opening of the tapered bore 28. Firing pin 27 has a bevelled shoulder 30, and between this shoulder and the tapering

wall of bore 28 is the barrier, shown in this instance as a rubber torus 31. Under centrifuging, the rubber ring will flatten out to free the pin, and will progress along the slant surface of the tapered bore 28. This type of fuse will remain armed because on cessation of rotation the rubber will contract to grip the pin above the shoulder in the groove 32. Two modifications of the pin are shown in Figure 4. On the left the pin is shown as movable forward of the fuse, while on the right the pin is shown as held against forward motion.

In Figure 5 there is shown a projectile body 33 having threadedly attached thereto a nose cap 34. The cap and body portions have complementary circular grooves 35 and 36 respectively, defining, when juxtaposed, an annular channel of generally hourglass section with a constricted portion 37. Cap 34 and body 33 have axial bores 38 and 39 respectively. Cap bore 38 has fitted therein the head 40 of a firing pin 41, and body bore 39 has fitted therein a primer 42. Fitted between the primer and the head 40 of pin 41 and surrounding the shank of the latter is a perforated rubber cylinder 43. This perforated cylinder has its outer periphery located in the opening into the channel. On rotation the rubber member will distend and be forced through the constriction 37 and into the outer chamber of the channel where it will remain trapped.

In Figure 6 is shown a projectile body 44 having an axial bore 45 opening forward thereof, a firing pin 46 slidably held in the bore, and a primer 47 fixed in the base of the bore. Extending through lateral bores 48 and intercepting the pin 46 are rubber centrifugal bolts 49. Lateral bores 48 are preferably tapered so as to flare outwardly. This type of fuse resembles a well-known type wherein metal centrifugal bolts are used, but the employment of rubber centrifugal bolts represents an improvement thereover, since they can be securely jammed into the bores and yet be easily loosened under centrifugal force due to volume flow. In other words, advantage is taken of the properties of rubber whereby it partakes of the characters of both fluids and solids.

In Figure 7 is shown a projectile body 50 having an axial bore 51 with an annular groove 52 in the side wall thereof. Slidably held in the forward portion of the bore 51 is a firing pin 53 and in the lower part thereof is a primer 54. Between the primer and the head 55 of the pin 53 is interposed a section of rubber tube 56. The columnar support furnished by the rubber tube is sufficient to hold the pin from contacting the primer under the shocks incident to ordinary handling. However, upon rotation, the rubber tube will distend into groove 52 thus eliminating direct columnar support and the pin will easily flex the distorted tube on impact, to fire the primer.

In Figure 8 is shown a fuse with a cylindrical tube rubber barrier 57 with longitudinal corrugations. In this case centrifuging distends the troughs 58 of the corrugations to free the pin 59.

In Figure 10 is shown a fuse similar to that of Figure 8 except that in this case the corrugations 60 are circumferential instead of longitudinal. Here the pin 61 is movable in ordinary handling but is limited to fall short of the primer when the rubber is subjected to compression alone. Upon rotation the path to the primer is cleared.

In Figures 11 and 12 are shown rubber barriers of stellate form designed to fit with their radial extremities into a cavity in a fuse, but having

open spaces 62 in its periphery to allow for distension on rotation. Perforations 63 in the body may also allow for distension.

We claim:

5. A fuse comprising a casing, a firing element and a barrier for said firing element in said casing, said barrier consisting essentially of a material with elastic properties similar to those of soft rubber and having a portion of its outer boundary spaced from the casing, said barrier constructed and arranged in said casing for volume distortion and a resultant distension of said portion of its outer boundary radially of the fuse axis under the urging of centrifugal force.

10 15. A fuse comprising a casing, a firing element and a barrier for said firing element in said casing, said barrier member comprising essentially a material with elastic properties similar to those of soft rubber, said barrier being coaxial with said casing and axially perforated, said barrier constructed and arranged in said casing for distension of at least a portion of its outer boundary radially of the fuse axis under the urging of centrifugal force, and means on the casing and contacting the barrier to rotate the barrier in unison with the casing.

20 25. A fuse as in claim 2 in which said contacting means comprise rod members arranged longitudinally of the casing and contacting the barrier at radial extremities thereof.

30 35. A fuse comprising a casing, a firing element and a barrier member for said firing element in said casing, said barrier member consisting essentially of a material with elastic properties similar to those of soft rubber, said barrier member being coaxial with said casing and axially perforated, said barrier member having at least a portion of its radial periphery spaced from the sides of said casing and other portions thereof contacting the sides of said casing to allow for distension of the barrier member radially of the fuse axis consequent upon its volume distortion under the urging of centrifugal force.

40 45. A fuse comprising a cylindrical casing with an annular groove in the inside wall thereof, a firing element and a barrier member for said firing element in said casing, said barrier member being of tubular form and fitted snugly into the casing, said barrier member comprising essentially a material with elastic properties similar to those of soft rubber, whereby the barrier member furnishes columnar support to resist motion of the firing element, but, under the urging of centrifugal force, distends into said annular groove to weaken the columnar support and permit flexing thereof and consequent displacement of the firing element.

50 55. A fuse comprising a casing, a firing element and a barrier for said firing element in said casing, said barrier member consisting essentially of a material with elastic properties similar to those of soft rubber, said barrier being coaxial with said fuse and axially perforated, said barrier occupying less than the whole of the cross section of said casing whereby, consequent upon its volume distortion upon rotation, it can distend in radial directions.

60 65. In a fuse, a firing element and a centrifugal safety blocking member therefor, said member composed of a material suffering sufficient elastic volume deformation under centrifugal action to unblock said member.
